(57) **CLAIM**

The ornamental design for the metatarsal phalangeal length restoration disc, as shown and described.

DESCRIPTION

FIG. 1 is a top perspective view of the metatarsal phalangeal length restoration disc comprising the new design;
FIG. 2 is a right side elevational view of the design of FIG. 1, where the left side elevational view is a mirror image;
FIG. 3 is a sectional elevational of the design of FIG. 1 taken along line 3-3 in FIG. 2;
FIG. 4 is a top view of the design of FIG. 1; and,
FIG. 5 is a bottom elevational view of the design of FIG. 1.
